US00D997225S

(12) **United States Design Patent** (10) **Patent No.:** **US D997,225 S**
(45) **Date of Patent:** **** Aug. 29, 2023**

(54) **SENSOR DEVICE**

(71) Applicant: **HTC Corporation**, Taoyuan (TW)

(72) Inventors: **Chang-Hua Wei**, Taoyuan (TW);
Chung-Wei Li, Taoyuan (TW)

(73) Assignee: **HTC Corporation**, Taoyuan (TW)

(**) Term: **15 Years**

(21) Appl. No.: **29/773,330**

(22) Filed: **Mar. 9, 2021**

(51) **LOC (14) Cl.** **16-01**

(52) **U.S. Cl.**

USPC **D16/200**

(58) **Field of Classification Search**

USPC D10/104.1, 109.1, 109.2; D16/202, 214,
D16/218, 244

CPC G03B 17/02; G03B 19/18; G03B 19/00;
G03B 2219/00

(57) **CLAIM**

The ornamental design for a sensor device, as shown and described.

DESCRIPTION

FIG. 1 is a perspective view of a sensor device showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is another perspective view thereof.

The broken lines shown in the drawings depict portions of the sensor device and form no part of the claimed design.

1 Claim, 8 Drawing Sheets
